UNITED STATES PATENT OFFICE

EMMA F. HUNT, OF NEW YORK, N. Y.

COMBINED COAT HANGER AND HAT STAND

Application filed August 2, 1929. Serial No. 383,007.

My invention relates to coat and hat hangers and refers more particularly to the combination of a folding coat hanger and hat stand.

5 One object of my invention is to provide a simple, effective coat hanger that is adapted to be folded and occupy a very small space.

Another object of my invention is to provide 10 a coat hanger that is adapted, when folded, to provide a hat stand.

A further object of my invention is to provide 15 a combined folding coat hanger and hat stand, the base of which is formed with a hook to simulate the head of an animal, bird, or the like.

A still further object of my invention is to provide 20 a combined coat hanger and hat stand that is comprised of a base and two arms which are adapted to be screwed into the base either to form a coat hanger or a hat stand.

It is well known in the art that coat hangers 25 have been made, but none of them incorporate the specific elements of this device, or have the same organization of particular parts.

I attain these results preferably by the 30 means illustrated in the accompanying drawing, wherein similar parts are referred to by like numerals throughout the several views, in which:—

Figure 1 is an elevation of one form of the device.

35 Figure 2 is an elevation of another form of the device.

Figure 3 is a plan of Figure 2.

Figure 4 is an elevation of Figure 2, positioned to form a hat stand.

40 The device in Figure 1 is comprised of a base 1, extended upwardly and formed to provide an opening 2 and a loop 3, which is adapted to hang the device up.

Extending outwardly from the vertical 45 centerline of the device are projections 4 and 5, the projection 4 circularly formed at 6 and provided with stops 7 and 8 for a bifurcated arm 9 which is pivoted at 10, and the projection 5 is formed circularly at 11, provided with stops 12 and 13, for

the bifurcated arm 14, pivoted at 15, and the bottom of this device is symmetrically formed at 16 so as to present an attractive appearance.

The arms 9 and 14, on each side of the 55 bifurcation, are extended outwardly at 17, 18, 19 and 20, respectively, and each arm is rounded at 21 and 22, in any suitable manner.

The device shown in Figure 2 is exactly 60 the same as shown in Figure 1, except that a loop 3 is done away with and the device is formed in the shape of a hook at 23, which hook may be made to simulate the head of an animal, bird, etc. 65

The device shown in Figures 1 and 2, illustrates the arms 9 and 14 positioned to be used as a coat hanger, and in Figure 3 the arms are positioned as shown, wherein the parts 17, 18, 19, and 20 serve as feet to support 70 the device when it is utilized as a hat stand.

In the device shown in Figures 1 and 2 the arms 9 and 14 provide feet for supporting the base 1 in a vertical position providing means for holding a hat. 75

Having thus illustrated and described the preferred embodiment of my invention, I do not wish to limit myself to the exact construction or arrangement of parts shown, since it is evident that modifications may be 80 made therein, without departing from the spirit of the invention or scope of the claim.

I claim:—

In a combination apparel hanger and 85 hat stand, a base formed to provide a hanging means, with bifurcated, pivoted arms, each side of the base piece having a sector and stops to provide means for engaging and positioning the said bifurcated arm against the stops, said arms positionable against said 90 stops, providing a hat stand.

Signed at New York, county of New York, State of New York, this 1st day of August, 1929.

EMMA F. HUNT. 95
